Specification for Design.

Patented May 5, 1914.

Application filed February 20, 1914. Serial No. 820,075. Term of patent 7 years.

To all whom it may concern:

Be it known that I, JOHN S. BURDICK, a citizen of the United States, and a resident of Bridgeport, county of Fairfield, State of Connecticut, whose post-office address is 3041 Main street, Bridgeport, Connecticut, have invented a new, original, and ornamental Design for Lamps, of which the following description, in connection with the accompanying drawings, is a specification.

In the drawing, Figure 1 shows a plan of a lamp having the design of my invention,

Fig. 2 a front elevation of the same, and Fig. 3 a side elevation.

What I claim is—

The ornamental design for a lamp, as shown.

In testimony whereof, I have signed my name to this specification, in the presence of two subscribing witnesses.

JOHN S. BURDICK.
